CLAIM

The ornamental design for a triangular splicing lamp, as shown and described.

DESCRIPTION

FIG. 1 is a front perspective view of a triangular splicing lamp design showing my new design.

FIG. 2 is a front view of the triangular splicing lamp.

FIG. 3 is a rear view of the triangular splicing lamp.

FIG. 4 is a left side view of the triangular splicing lamp.

FIG. 5 is a right side view of the triangular splicing lamp.

FIG. 6 is a top view of the triangular splicing lamp.

FIG. 7 is a bottom view of the triangular splicing lamp.

FIG. 8 is a rear perspective view of the triangular splicing lamp; and,

FIG. 9 is a front perspective view thereof, showing the triangular splicing lamp in a separated state of use.

The broken lines in the drawings depict portions of the triangular splicing lamp that form no part of the claimed design.
